UNITED STATES PATENT OFFICE

FRANCIS M. AIMES, OF HUDSON, NEW YORK, ASSIGNOR TO GIFFORD-WOOD COMPANY, OF HUDSON, NEW YORK, A CORPORATION OF NEW YORK

PORTABLE ICE UP-ENDING MACHINE

Application filed August 19, 1930. Serial No. 476,336.

This invention relates to portable ice up-ending machines, that is, machines for turning commercial ice cakes from an "on edge" position to a position "on end".

Among other objects, the invention aims to provide a very simple machine for automatically up-ending ice cakes which may be used with a minimum of labor on the part of the attendant and which may be easily transported to different parts of an ice plant, yet may rest immovably at any desired point on the floor of the plant. The present invention also provides a machine which is set very close to the floor line so that a minimum of labor is necessary to supply it with ice cakes to be up-ended. The machine of the invention is particularly useful in conjunction with one or more ice scoring machines, but may be used at any place where up-ending of the cakes is advantageous.

Referring to the accompanying drawings forming a part of this specification and showing a preferred embodiment of the invention,

Fig. 1 is a side elevation of the up-ending machine;

Fig. 2 is a horizontal section substantially on line 2—2 of Fig. 1 but on a larger scale;

Fig. 3 is a vertical section substantially on the line 3—3 of Fig. 1 but on a larger scale;

Fig. 4 is a vertical section substantially on the line 4—4 of Fig. 1 but on a larger scale;

Fig. 5 is a vertical section substantially on the line 5—5 of Fig. 1 but on a larger scale;

Fig. 6 is a vertical section substantially on line 6—6 of Fig. 1 but on a larger scale;

Fig. 7 is a vertical section through the discharge chute, the section line being indicated at 7—7 of Fig. 1 but on a larger scale;

Fig. 8 is a simplified wiring diagram showing the motor control;

Fig. 9 is a vertical section substantially on line 9—9 of Fig. 1 but on a larger scale; and

Fig. 10 is a diagram illustrating, as in side elevation, the manner in which the up-ending of the cakes is performed.

In the drawings, the reference numeral 15 designates the frame or chassis of the machine and 16 designates an upright yoke secured to the frame 15 at one end and forming a part thereof, the yoke being sufficiently wide

to permit ice cakes to pass therethrough when standing on end and presented edgewise. The frame 15 and 16 is preferably made up of angle bars, as shown, which may be welded together to form a strong structure for supporting the working parts of the machine.

The preferred machine is of the ambulatory type and hence is provided with a pair of wheels 17 at one end of the frame 15 and a pair of swiveled casters 18 at the opposite end. Said casters are provided so that the machine may be supported by other means providing temporary legs preventing movement of the machine when in use, as will be described. Fig. 1 shows the casters 18 supported off the floor so that the machine is temporarily immovable.

To facilitate feeding and discharge of the ice cake, a slide or chute 19 is at one end of the machine, and a similar slide or chute 20 is at the other end. Both chutes are channel-shaped (Figs. 2 and 7) and have a width but slightly exceeding the thickness of a standard ice cake, each chute being in alignment with the longitudinal axis of the machine, thus facilitating unidirectional movement of the ice cakes through the machine.

The chute 19 extends from a point resting on the floor upwardly at a slight angle to a point between the large wheels 17. At the upper end of chute 19, a roller 21 (Figs. 2 and 3) may be provided, said roller being mounted on a shaft 22 extending transversely of the machine. After the center of gravity of the ice cake has passed the roller 21, the cake tilts

and moves downwardly on inclined guides 23 formed of angle bars, best shown in Figs. 2 and 4, said angle bars being rigidly secured to the frame 15 and providing two spaced vertical flanges for engagement with the opposite faces of the ice cake to prevent lateral movement thereof. The angles 23 provide a downwardly inclined support for the ice cake which rests on edge immediately before being turned to an "on end" position by the

machine. It will be noted that the angles 23 are in alignment with the chutes 19 and 20 and have their flanges spaced apart the same distance as the vertical flanges of the chutes. Movement of the ice cakes down guides 23

100

past a certain point is prevented by a stop to be described.

In the illustrative machine, the up-ending operation is performed by means of a chain conveyor comprising a pair of chains 24 having a flight 25 (Figs. 2 and 9) secured to and extending between them. The two chains 24 lie in spaced vertical planes extending longitudinally of the machine on each side of the path of the cake so that the ice cake may move freely between them without interference. However, the flight 25 is so guided by the chains 24 that it may engage under the ice cake when resting on the supports 23, the point of engagement being at the end of the cake nearest the chute 19 and the result, as shown in Fig. 10, being to lift and turn the cake about the end (which rests against the above-mentioned stop, adjacent the chute 20), finally placing the up-ended cake at the receiving end of chute 20. In order to effect this result, the chains 24 are each guided by at least three sprockets 26, 27 and 28, the sprockets 26 and 27 being idler sprockets mounted on the frame 15, 16 and the sprockets 28 being drive sprockets, as will be described. Preferably, the sprockets 26 are made adjustable to take up slack in the chains, there being an adjustment screw 29 for each sprocket 26. Preferably the sprocket 26 and associated parts are mounted on upright frame members 30 secured to the frame 15.

The means for driving the flight conveyor comprises a motor 31 (Figs. 1 and 2) mounted on the frame, a speed reducer unit 32, a sprocket 33 driven from the speed reducer, a sprocket chain 34 driving a sprocket 35, said sprocket being secured on shaft 22 to which the sprockets 28 are also secured, as best shown in Fig. 3. By means of switches to be described, the motor is started and stopped and effects movement of the flight 25 upwardly in an inclined path between the sprockets 28 and the sprockets 26 and then horizontally between the sprockets 26 and 27, finally pushing the up-ended cake on the upper end of chute 20.

Before the ice cake is tilted by the flight 25, its forward end abuts a stop 36 preferably in the form of a curved plate, as shown in Figs. 1, 2 and 4. Upward lifting on one end of the cake causes the lower end resting against stop 36 to move over the curved surface of said stop as an axis or fulcrum, the cake shifting on its lower end as it nears the vertical or "on end" position, finally standing on end on the chute 20. This process is clearly illustrated in Fig. 10. In the up-ending operation, the cake is prevented from moving laterally by means of longitudinally extending guides 37, preferably curved as shown in Fig. 1, and secured to the upright frame members 16 and 30 and also, if desired, to other intermediate uprights 38. The guides 37 may extend so far as to overhang the chutes 19

and 20 respectively, as shown, and in this event, their ends are supported by braces 39 and 40 at the opposite ends of the machine.

While the motor could be operated by means of a hand switch, it is preferred to make the operation of the machine entirely automatic and this is accomplished in the illustrative example by means of a switch constructed and arranged to be closed as soon as the ice is on the supports 23 so as to start the conveyor, together with a limit switch stopping the conveyor after the ice cake has been up-ended. Referring to Figs. 1, 2 and 6, there is shown a pivoted yoke 41 having a central portion 42 which the lower edge of each ice cake engages, so as to move the yoke 41 downwardly to the position of Fig. 6. The downward movement of yoke 41 closes a switch 43 which, as shown in Fig. 8, controls the circuit of the motor 31 through a relay 44. The conductors 45 leading to the motor 31 are connected through the relay 44 with a contact block 46 (Figs. 1 and 8) providing convenient means for making an electrical connection with a cable (not shown) containing the leads 47. The cable may be of any convenient length so as to connect the machine with the source of electrical supply, irrespective of the position of the machine in the plant.

After the conveyor has up-ended the ice cake, the conveyor continues to move until the flight 25 is put in position to engage with the succeeding ice cake on the under edge thereof. To effect stoppage of the motor and conveyor, a limit switch 48 has a movable arm 49 (Figs. 1, 2, 8 and 9) in the path of flight 25. When the flight 25 engages the arm 49, the motor circuit is broken and the motor and conveyor quickly stopped. Thus the machine starts the up-ending operation as soon as an ice cake is in the proper position and effects stoppage of the conveyor when the flight is substantially in position to engage the succeeding cake of ice, and when it is entirely out of the way of the succeeding cake.

As the machine is designed to be portable, the chutes 19 and 20 are preferably pivoted to the opposite ends of the frame 15, as clearly shown in Figs. 1 and 2. Each chute may be swung upwardly nearly to a vertical position and latched by means of a latch 50, 51, each latch being pivoted on one of the guides 37. Each chute may have a laterally projecting pin 52 (Figs. 1 and 7) with which the corresponding latch may engage. However, the particular chute-latching means is of no importance.

In order to support the machine off the casters 18 so that the machine may be immovable, shoes 53 are provided, as shown in Figs. 1, 4 and 5. The shoes 53 are pivoted eccentrically on a transverse shaft 54 and preferably are rigidly secured to the chute 20 in

such a manner as to effect raising of the machine off the casters 18 when the chute 20 is lowered into contact with the floor. However, when the chute 20 is swung upwardly into the dotted line position of Fig. 1, the shoes 53, being swung in a counterclockwise direction, as viewed in Fig. 1, are clear of the floor because of their shape and the casters 18 are lowered into contact therewith. Then 10 the machine may be moved from place to place by the operator, the swiveled casters facilitating guiding of the machine by hand.

Obviously, the present invention is not restricted to the particular embodiment thereof herein shown and described. Moreover, it is not indispensable that all the features of the invention be used conjointly, since they may be employed advantageously in various combinations and sub-combinations.

20 What I claim is:—

1. An ice up-ending machine comprising, in combination, a frame providing a downwardly inclined stationary support for the ice cakes on edge; a stop carried on the frame 25 at the lower end of said downwardly inclined support; and motor-driven means on the frame engaging under the bottom edge of the ice cake when on said support to lift the higher end of the cake upwardly and to turn it through an arc of 90° about the stop as an axis until it stands on end.

2. An ice up-ending machine comprising, in combination, a frame providing a downwardly inclined stationary support for the 35 ice cakes on edge; a stop carried on the frame at the lower end of said downwardly inclined support, and a power driven endless chain conveyor on the frame having a flight engaging under the bottom edge of the ice cake when on said support to lift the higher end of the cake upwardly and to turn it through an arc of 90° about the stop as an axis until it stands on end.

3. An ice up-ending machine comprising, 45 in combination, a frame providing a downwardly inclined support for the ice cakes on edge, a stop carried on the frame at the lower end of said downwardly inclined support; an endless chain conveyor on the frame having a flight engaging under the bottom edge of the ice cake when on said support to lift the higher end of the cake upwardly and to turn it about the stop as an axis until it stands on end; said conveyor comprising two 55 chains with the flight extending between them; and sprockets for guiding, driving and supporting the chain conveyor, there being three of said sprockets on each side of the machine so that each chain is generally triangular in elevation; the flight when lifting the cakes moving upwardly in an inclined path and then substantially horizontally.

4. An ice up-ending machine comprising, 60 in combination, a frame providing a stationary support for the ice cakes on edge; an end-

less chain conveyor on the frame having a flight whose path at one point is underneath and at one end of the cake when supported on the frame; said conveyor guiding and driving the flight so as to lift and turn the ice cake 70 through an arc of 90° from "on edge" to "on end"; and a chute arranged to receive and discharge the ice cakes after the up-ending operation.

5. An ice up-ending machine comprising, 75 in combination, a frame providing a stationary support for the ice cakes on edge; an endless chain conveyor on the frame having a flight whose path at one point is underneath and at one end of the cake when supported on the frame; said conveyor guiding and driving the flight so as to lift and turn the ice cake 80 through an arc of 90° from "on edge" to "on end"; a slide for guiding the ice cakes, when pushed "on edge", to a position on the support, and a chute receiving and discharging the ice cakes after the up-ending operation.

6. An ice up-ending machine comprising, 85 in combination, a frame providing a support for 90 the ice cakes on edge; an endless chain conveyor on the frame having a flight whose path at one point is underneath and at one end of the cake when supported on the frame; said conveyor guiding and driving the flight 95 so as to lift and turn the ice cake from "on edge" to "on end"; a slide for guiding the ice cakes, when pushed "on edge", to a position on the support; and a chute receiving and discharging the ice cakes after the up-ending 100 position; the slide and the chute being at opposite ends of the support so that the ice cakes may move uni-directionally, and being hinged thereto so that both may be folded when the machine is being moved about.

7. An ice up-ending machine comprising, 105 in combination, a frame providing a support for the ice cakes on edge; an endless chain conveyor on the frame having a flight whose path at one point is underneath and at one end of the 110 cake when supported on the frame; said conveyor guiding and driving the flight so as to lift and turn the ice cakes from "on edge" to "on end"; a motor for driving said conveyor; a switch in the motor circuit and carried on the frame and so constructed and arranged that it is closed by an ice cake when positioned on the frame for turning; and a limit switch also in the motor circuit constructed and arranged to stop the motor after the ice cake is 115 up-ended.

8. An ice up-ending machine comprising, 120 in combination, a frame providing a support for the ice cakes on edge; an endless chain conveyor on the frame having a flight whose 125 path at one point is underneath and at one end of the cake when supported on the frame; said conveyor guiding and driving the flight so as to lift and turn the ice cake from "on edge" to "on end"; a motor for driving said conveyor;

a switch in the motor circuit and carried on the frame and so constructed and arranged that it is closed by an ice cake when positioned on the frame for turning; and a limit switch 5 also in the motor circuit and carried on the frame with a part projecting in the path of the flight so as to be actuated by the flight to stop the motor after the ice cake is up-ended.

9. An ice up-ending machine comprising, 10 in combination, a frame; a power driven conveyor on the frame having means so guided that it engages under a cake on edge at one end thereof and lifts the cake to an "on end" position; a chute for the discharge of the 15 up-ended cakes which is hinged to the frame; and means moved by swinging the chute to project below the frame to provide effectively a pair of legs for the machine.

10. An ice up-ending machine comprising, 20 in combination, a frame; a power driven conveyor on the frame having means so guided that it engages under a cake on edge at one end thereof and lifts the cake to an "on end" position; a chute for the discharge of the up-ended cakes which is hinged to the frame; 25 a pair of wheels at one end of the frame; a pair of casters adjacent the hinge of the chute; and means moved by swinging the chute to project below the frame to provide effectively a pair of legs for the machine; 30 said means lowering the machine to rest on the casters when the chute is swung upwardly.

11. An ice up-ending machine comprising, 35 in combination, a frame providing a support for the ice cakes on edge; an endless chain conveyor on the frame having a flight whose path at one point is underneath and at one end of the cake when supported on the frame; 40 said conveyor guiding and driving the flight so as to lift and turn the ice cake from "on edge" to "on end"; a slide for guiding the ice cakes, when pushed "on edge", to a position on the support; a chute receiving and 45 discharging the ice cakes after the up-ending position; the slide and the chute being at opposite ends of the support so that the ice cakes may move uni-directionally, and being hinged thereto so that both may be folded 50 when the machine is being moved about; guides for the ice cake during the up-ending operation, said guides being secured rigidly to and extending longitudinally of the frame.

12. An ice up-ending machine comprising, 55 in combination, a frame providing a support for the ice cakes on edge; an endless chain conveyor on the frame having a flight whose path at one point is underneath and at one end of the cake when supported on the frame; 60 said conveyor guiding and driving the flight so that the flight unaided lifts and turns the ice cake through an arc of 90° from "on edge" to "on end"; an abutment providing a fulcrum for the ice cake when so turned; a chute 65 arranged to receive and discharge the ice

cakes after the up-ending operation; and curved guides extending longitudinally of and secured to the frame to prevent substantial lateral movement of the ice cakes during up-ending and when moved onto the chute. 70

13. An ice-up-ending machine comprising, in combination, a frame providing a support for the ice cakes on edge; an endless chain conveyor on the frame having a flight whose path at one point is underneath and at one 75 end of the cake when supported on the frame; said conveyor guiding and driving the flight so that the flight unaided lifts and turns the ice cake, when abutted against a fixed member providing a fulcrum, through an arc of 80 90° from "on edge" to "on end".

In testimony that I claim the foregoing as my own, I have hereto affixed my signature.

FRANCIS M. AIMES.
